UNITED STATES PATENT OFFICE.

ALBERT Y. TUCKER, OF MOUNT VERNON, NEW YORK, AND JOHN E. CONGDON, OF PASSAIC, NEW JERSEY, ASSIGNEES TO THE NEW YORK BELTING & PACKING COMPANY, A CORPORATION OF NEW YORK.

PRESS FOR MOLDING PLASTIC ARTICLES.

1,332,963.

Specification of Letters Patent.

Patented Mar. 9, 1920.

Continuation of application Serial No. 152,170, filed March 3, 1917. This application filed September 27, 1917.
Serial No. 193,480.

To all whom it may concern:

Be it known that we, ALBERT Y. TUCKER, a citizen of the United States, and residing at Mount Vernon, county of Westchester, 5 and State of New York, and JOHN E. CONGDON, a citizen of the United States, and residing at Passaic, county of Passaic, and State of New Jersey, have invented certain 10 new and useful Improvements in Presses for Molding Plastic Articles, of which the following is a full, clear, and exact description.

This invention relates to multiple presses and particularly to presses of that type employed for vulcanizing molded rubber goods. 15 Such presses customarily embody a plurality of platens spaced apart to provide intervening openings adapted for the reception of molds to be operated upon. In operating such presses the several platens are loaded with molds suitably charged with the material to be vulcanized; the press is then closed and the molds are subjected to the required 20 degree of heat imparted by the press for a sufficient period of time to effect the desired vulcanization. The period of time required for vulcanization varies depending upon certain requirements and conditions, for instance, rubber compounded for one type of 25 shoe soles requires a period of ten minutes to vulcanize, while rubber compounded for other types of soles may be vulcanized in a period of seven minutes.

An object of the present invention is to provide a multiple vulcanizing press and feeding means therefor adapted to take care of the full output of two or more operators working on different sides of the press, thereby obviating the periods of delay heretofore incident to the operation of multiple 40 presses.

In accomplishing this object a series of molds is provided for each opening in the press, the arrangement of each series being such that while one or more of the molds thereof is confined within the press the remainder will be disposed without the press in a position permitting loading and unloading. Thus while one portion of the series 45 is being subjected to the action of the press the remainder thereof is disposed without the press in a position permitting its contents to be removed and a new charge in-

stalled. The several series of molds are preferably so arranged that their outwardly disposed portions will be alternately positioned on different sides of the press so that when one operator from his side of the press is loading a portion of one series the operator on the other side of the press will be 60 unloading a portion of the next adjacent series, and likewise when one operator is removing that portion of one series which has been subjected to the action of the press the operator on a different side of the press will 65 be withdrawing that portion of the next adjacent series which has been subjected to the action of the press. To attain this end each series of molds is mounted for movement along suitable runways arranged in alignment with the openings in the press. In the preferred embodiment two runways are provided for each opening, one being disposed on the opposite side of the press from the other. It is to be understood, however, that 70 the number of runways provided for each opening may be varied and that their arrangement may be modified as desired.

Although in some forms of construction each of the molds of a series may be entirely independent one from the other, in the preferred embodiment of the invention it is desirable to couple them together so that they may be moved in unison whereby when one portion of a series is removed from its respective opening the remainder thereof will be simultaneously inserted into the opening. By coupling the molds together the operation of loading and unloading the press will be greatly facilitated as alternate series of 80 molds may be moved in opposite directions so as to insert newly charged molds into the press at the same time that those molds which have been previously operated upon are removed from the press. Another advantage of this construction is that the workmen stationed at different sides of the press may be engaged in charging and discharging the outwardly disposed portion of each alternate series while the remaining 85 portions of such series are being operated upon by the press.

While it is feasible to have each series of molds entirely independent of the others it is preferred to provide means for coupling 90 the series together in pairs so that when one

series is moved the companion series will be simultaneously moved in an opposite direction. In presses having more than two openings the respective series of molds may be connected together in such a way that alternate series will be moved simultaneously.

As it is desired that each operator be continuously employed in discharging and 10 charging molds the size of the press and consequently the number of molds used may be so varied that the number of molds disposed without the press will be such as to require a period of time to charge and re- 15 charge corresponding to the period of time required to effect the desired vulcanization of the articles in the press. This result may also be accomplished by varying the number of openings in the press. If a press having 20 a relatively large number of openings is used each operator may take care of several series of molds.

Having set forth some of the important 25 features of the invention a detail description 30 of one of the preferred embodiments thereof will now be given, reference being had to the accompanying drawings, in which—

Figure 1 is a side elevation of a press provided with the improvements;

Fig. 2 is a cross-sectional view on the line 2—2 of Fig. 1.

Fig. 3 is a diagrammatic view of the 35 pressing members, molds, carriers, and means connecting the carriers.

The press shown in the drawings comprises superposed platens or pressing members 10, 11, and 12. The upper pressing member 10 is secured to a base 13 by tie rods 40 14. The lower pressing member 12 is supported upon a ram 15. The intermediate pressing member 11 is provided on the side with projections 16 which bear on stops 17 carried by rods 18 and normally support 45 the member at its lowest limit of movement. These parts are characteristic of an ordinary vulcanizing press in connection with which the present embodiment of the invention will be described. In presses of this 50 type means is provided to heat the pressing members but for the sake of brevity a description of the same will be dispensed with.

In carrying out the invention we provide superposed mold carriers 19 and 20, arranged in tiers, or superposed with respect 55 to each other, the upper carrier 19 being positioned to move through the opening between the upper pressing member 10 and the intermediate pressing member 11, and the lower carrier 20 being positioned to move 60 through the opening between the intermediate pressing member 11 and the lower pressing member 12. The upper carrier is adapted to support a series of duplicate molds 21 and 22, and the lower carrier is adapted to

support a series of molds 23 and 24. In the present embodiment, recessed molds suitable for use in vulcanizing rubber soles are illustrated, each comprising a body *a* and a cover *b*, the cover being preferably hinged to the 70 corresponding carrier for convenience. However, the apparatus is not limited to the use of such molds. Preferably each carrier is formed with depressions to retain and locate the corresponding molds, as best 75 shown at 21' and 22' in Fig. 2. Each carrier is of such length, and the molds are so spaced apart thereon, that when the carrier is moved to withdraw one mold from between the pressing members, the mating 80 mold is set between the pressing members.

In further carrying out the invention the superposed carriers 19 and 20 are connected together for simultaneous movement in opposite directions whereby to dispose certain 85 of the molds of the respective series between the pressing members and others outside of the pressing members on opposite sides of the press. To accomplish this, endless connectors are provided, one on each end of the 90 press, each comprising a sprocket chain 25, running over sprocket wheels 26 and 27 carried by brackets 28 fixed to the tie rods 14. The upper portion of the chain is connected by a pin 29 to the upper mold carrier 19 at 95 about the center of the edge thereof, and the lower portion of the chain is connected by a pin 30 to the lower mold carrier 20 at about the center of the edge thereof. Opposed pairs of sprocket wheels 26, 27 of both 100 endless connectors are mounted on common shafts 26', 27' so that the two runs of the endless connectors will move in unison in opposite directions.

By now referring to Fig. 3 it will be seen 101 that when the upper mold carrier 19 is moved toward the right the mold 22 is withdrawn from between the pressing members 10 and 11 and the mold 21 is set between said pressing members. At the same time 110 the endless connectors have moved the lower mold carrier 20 to the left so that the mold 24 is withdrawn from between the pressing members 11 and 12 and the mold 23 is set between said pressing members. The molds 115 22 and 24, as shown by dotted lines, will then be outside of the press on opposite sides of the press where operators working simultaneously remove the pressed product from them, and charge the molds with the 120 requisite material to be subsequently pressed. By reversing the above described movement of the parts, the mold carriers withdraw the pressed molds from between the pressing members and simultaneously 125 set the charged molds between the pressing members.

The mold carriers may be moved manually if desired, but preferably are power moved, and to attain this end there is pro- 130

vided on each end of the press a cylinder 31 for a fluid under pressure, the cylinder being equipped with a piston which is connected to the lower mold carrier 20 by 5 a rod 32 and a bracket 33. The fluid under pressure is admitted to the ends of the cylinder through pipes 34, 35 and 36, there being a valve 37 in the pipe 35 for selectively admitting the fluid to either end of 10 the cylinder and releasing it from the other end according to the desired direction of movement of the mold carriers. Pipe 36 carries off exhaust.

For supporting the weight of the molds 15 when outside of the press, superposed supports, such as runways 38 and 39, are arranged on opposite sides of the press as best shown in Fig. 1. The upper runways 38 are disposed just below the path of movement 20 of the upper mold carrier, and the lower runways 39 are disposed just below the path of movement of the lower mold carrier. As shown in Figs. 1 and 2, when a mold is supported by the upper runway on one side of 25 the press, a mold will be supported at the same time by the lower runway on the opposite side of the press. To provide access to the mold supported by the lower runway the runway above it must be displaced and to 30 attain this end, each upper runway is preferably mounted at one end on pivot pins 40 secured to stationary brackets 41 so that the runway may be swung upward as shown in Fig. 1 and expose the mold on the runway 35 beneath it. Preferably the free end of each pivoted upper runway is supported by legs 42 that bear upon the runway beneath it, and also the free end of each lower runway is preferably rigidly supported by legs 43.

40 In certain forms of construction the mold carriers 19 and 20 may be dispensed with, the molds being supported directly on the runways. Various other types of runways than that illustrated may also be used, for 45 instance each runway may consist of two parallel tracks adapted to support the molds. If desired the lower runways 20 may be made longer than the upper ones 19 so that the lower series of molds may be moved to 50 a position in advance of the upper series permitting the operators to discharge and charge it without the necessity of lifting the upper runways.

This application is a continuation of our 55 allowed application, Serial No. 152,170, filed March 3, 1917.

While we have described some of the preferred embodiments of our invention it is to be understood that various modifications 60 may be resorted to within the scope of the appended claims without departing from the spirit or sacrificing any of the advantages of the invention.

Having thus described our invention, what 65 we desire to protect by Letters Patent is:—

1. The combination in a press, of superposed pressing members, superposed movable mold carriers adapted to carry a plurality of molds, and means connecting said carriers for simultaneous movement in opposite directions whereby to dispose certain of the molds between the pressing members and others outside of the pressing members on opposite sides of the press. 70

2. The combination in a press, of superposed pressing members, superposed movable mold carriers adapted to carry a plurality of molds, and an endless connector having its upper portion connected with one carrier and its lower portion with another carrier and serving to connect said carriers for simultaneous movement in opposite directions whereby to dispose certain of the molds between the pressing members and others outside of the pressing members on opposite sides of the press. 75

3. The combination in a press, of superposed pressing members, superposed movable mold carriers adapted to carry a plurality of molds, upper and lower supports 80 for the carriers disposed outside of the pressing members on opposite sides of the press, means permitting of said upper supports being displaced to permit access to said lower supports, and means connecting said carriers for simultaneous movement in opposite directions whereby to dispose certain of the molds between the pressing members and others outside of the pressing members on corresponding supports on opposite 85 sides of the press. 90

4. The combination in a press, of superposed pressing members, superposed movable mold carriers adapted to carry a plurality of molds, upper and lower supports 100 for the carriers disposed outside of the pressing members and on opposite sides of the press, pivots at one end of each upper support upon which the support may be swung up to expose the lower support beneath it, and means connecting said carriers for simultaneous movement in opposite directions whereby to dispose certain of the molds between the pressing members and others outside of the pressing members on corresponding supports on opposite sides of the press. 105

5. The combination in a press, of superposed pressing members, superposed movable mold carriers adapted to carry a plurality of molds, fluid operative means for moving the carriers, and an endless connector having its upper portion connected with one carrier and its lower portion connected with another carrier and serving to connect said carriers for simultaneous movement in opposite directions whereby to dispose certain of the molds between the pressing members and others outside of the pressing members on opposite sides of the press. 110

6. The combination in a press, of super- 115

- posed pressing members, superposed movable mold carriers adapted to carry a plurality of molds, upper and lower supports for the carriers disposed outside of the pressing members on opposite sides of the press, fluid operative means for moving said carriers, means permitting of said upper supports being displaced to permit said access to said lower supports, and means connecting said carriers for simultaneous movement in opposite directions whereby to dispose certain of the molds between the pressing members and others outside of the pressing members on corresponding supports on opposite sides of the press.
7. The combination in a press, of superposed pressing members, superposed movable mold carriers adapted to carry a plurality of molds, upper and lower supports for the carriers disposed outside of the pressing members and on opposite sides of the press, pivots at one end of each upper support upon which the support may be swung up to expose the lower support beneath it, fluid operative means for moving the carriers, and means connecting said carriers for simultaneous movement in opposite directions whereby to dispose certain of the molds between the pressing members and

others outside of the pressing members on 31 corresponding supports on opposite sides of the press.

8. In a multiple press, in combination, a plurality of superposed pressing members, a plurality of mold carriers each operatively supported for movement between contiguous pressing members, and means for simultaneously moving said mold carriers in opposite directions to dispose certain of the molds between the pressing members and others 40 outside of the pressing members in an accessible position on opposite sides of the press, said last named means including an endless driving member operatively connected with adjacent mold carriers, rotary members supporting said endless driving member and being fixedly supported at opposite sides of a pressing member which is located intermediate the movable mold carriers connected to said endless driving member. 45
